UNITED STATES PATENT OFFICE.

OTIS B. CROSSMAN, OF CHARTLEY, MASSACHUSETTS, ASSIGNOR TO BATES & BACON,
OF ATTLEBORO, MASSACHUSETTS.

DESIGN FOR A LINK FOR ORNAMENTAL CHAINS.

40,775.

Specification for Design.

Patented July 19, 1910.

Application filed May 13, 1910. Serial No. 561,263. Term of patent 3½ years.

To all whom it may concern:

Be it known that I, OTIS B. CROSSMAN, a citizen of the United States, residing at Chartley, in the county of Bristol and State of Massachusetts, have invented a new, original, and ornamental Design for a Link for Ornamental Chains, reference being had to the accompanying drawing.

The figure in the drawing is a perspective view of a link, showing my design.

I claim—

The ornamental design for a link for ornamental chains, as shown.

OTIS B. CROSSMAN.
